Attorney.

UNITED STATES PATENT OFFICE.

NEWELL T. FOGG, OF SANFORD, MAINE.

TORPEDO-NETTING.

1,271,689.

Specification of Letters Patent.

Patented July 9, 1918.

Application filed May 7, 1917. Serial No. 166,950.

To all whom it may concern:

Be it known that I, NEWELL T. Fogg, a citizen of the United States, and a resident of Sanford, in the county of York and State 5 of Maine, have invented certain new and useful Improvements in Torpedo-Nettings, of which the following is a specification.

This invention relates to means for protecting vessels from dirigible torpedoes, 10 mines and the like, and has for its object the construction of a protecting means of this nature which may be carried by a vessel when not in a danger zone, and thereby kept from being a drag upon the speed thereof; 15 which may be kept in reserve at the outskirts of a danger zone for immediate protection of a ship entering the same; which may at will be employed as a mine sweeper and netting either independently or jointly, and which 20 shall embody other details of improvement hereinafter set forth.

In the drawings forming part of this specification, Figure 1 is a side view of a steamship carrying the protecting means 25 submerged. Fig. 2 is a plan view of the vessel showing the protecting means in defensive operation, both against torpedoes and mines. Fig. 3 is a side view of one of the units which composes the protecting means. 30 Fig. 4 is a sectional view of the ball-and-socket connection between a net and one of its supporting and propelling boats. Fig. 5 is a modified form of the invention.

My invention consists essentially of a 35 series of netting units each provided with both a supporting and a dirigible means. As illustrated in Fig. 1, such a unit comprises a suitable frame 1 and netting 2 of any desired type, and a power boat 3 at each 40 end thereof. The frame is connected with each boat by means of two goose-neck bars 4 meeting at a ball 5 confined in a socket 6 suitably fastened to the keelson of the same, as shown at the right hand end of the unit in 45 Fig. 3.

Thus connected, and each goose-neck 4 being spaced far enough apart from its neighbor to allow ample room for the boat 3, each boat can pitch, toss and roll as freely 50 as may be necessary, and can also be steered in any direction, or turned end for end, or at right angles to the plane of the netting.

These units can be supported upon davits in a well known manner and carried free of 55 the water by the ship 9, as indicated in Fig. 1, until such time as a danger zone is reached,

and can then be lowered to the surface of the sea, with one man in each boat 3. According to pre-arrangement, the men guide their power boats into an overlapping line 60 at each side of the steamship, at distances of twenty-five or fifty feet from the latter, and urging their engines to the requisite speed, maintain the relative positions until the danger zone is passed. If a torpedo 65 meets and is exploded by one of the units and the netting and perhaps one of its boats put out of commission, the remaining units can be positioned to fill the gap and continue to protect the vitals of the vessel, and one 70 or two units can come around from the other side of the steamship and lend their aid to the attacked units.

If preferred, a large number of the protective units can be held at the margin of 75 a danger zone and assembled to shield and pilot any approaching vessel.

One or more such units can be made to propel the netting at right angles to the forward direction of the boats 3, and thereby 80 to protect the following vessel from floating or anchored mines, as shown at the right hand end of Fig. 2.

At times it is desirable to render the power boats 3 fixed in their alignment with the 85 netting. For example, should the man operating one boat be shot or otherwise incapacitated from steering it, the man in the other boat can at once climb along the bar 14, balancing himself by the hand-rail 15, 90 and engage the two arms 16, 17 with the goose-neck 4. He can then return to his own boat and trail the netting and the other boat after him.

In the construction shown in Fig. 5, the 95 ball and socket 5, 6 is bolted to the under surface of the keel of each power boat, and the netting frame connected directly therewith by the vertical rod-members 19.

It will be observed that in this construction, as well as in that first described, the boats can not only be reversed in direction, but can be turned to positions transverse to the netting.

What I claim is:

1. A protection against torpedoes and the like, comprising a comparatively inflexible frame, intercepting means carried by said frame, and a boat pivotally connected to each end of said frame, the pivotal connection to each boat being at substantially its longitudinal and transverse center and 110

adapted to permit the boat to be turned to any point in the compass independently of the frame.

2. A protection against torpedoes and the like, comprising a comparatively inflexible frame, intercepting means carried by said frame, and a buoyant supporting means pivotally connected to each end of the frame to permit each means to be turned to any point in the compass independently of said frame, and means for locking either supporting means in alignment with said frame.

3. A protection against torpedoes and the like, comprising a comparatively inflexible frame, intercepting means carried by said frame, and a boat pivotally connected to each end of said frame, the pivotal connection embracing in each case a ball and socket adapted to permit the boat to be guided in any direction relative to the said frame.

4. A protection against torpedoes and the like, comprising a comparatively inflexible frame, intercepting means carried by said frame, and a boat pivotally connected to

each end of said frame, the pivotal connections being adapted to permit the boats to be turned to any points in the compass independently of said frame.

5. A protection against torpedoes and the like, comprising an elongated frame, netting stretched across the same, two spaced goose-necks rising from each end of the frame, a ball rigid with the extremes of each pair of goose-necks, a socket loosely fitting each ball, and power boats each having a socket attached to its keelson, the length of each power boat being less than the space between the connected goose-necks to permit the same to turn in any direction horizontally relative to the frame.

In testimony that I claim the foregoing invention, I have hereunto set my hand this 3rd day of May, 1917.

NEWELL T. FOGG.
